US010500473B2

(12) **United States Patent**
Watterson

(10) **Patent No.:** **US 10,500,473 B2**
(45) **Date of Patent:** **Dec. 10, 2019**

(54) **CONSOLE POSITIONING**

- (71) Applicant: **ICON Health & Fitness, Inc.**, Logan, UT (US)
- (72) Inventor: **Scott R. Watterson**, Logan, UT (US)
- (73) Assignee: **ICON Health & Fitness, Inc.**, Logan, UT (US)
- (*) Notice: Subject to any disclaimer, the term of this patent is extended or adjusted under 35 U.S.C. 154(b) by 130 days.

(21) Appl. No.: **15/712,883**

(22) Filed: **Sep. 22, 2017**

(65) **Prior Publication Data**

US 2018/0099205 A1 Apr. 12, 2018

Related U.S. Application Data

(57) **ABSTRACT**

A method for positioning a console of an exercise device includes determining an angle formed between an exercise deck of the exercise device and a base of the exercise device and adjusting a physical height of a console of the exercise device to a correlated height based at least in part on the angle of the exercise deck when the physical height is determined to be out of alignment with the correlated height.

CONSOLE POSITIONING

RELATED APPLICATIONS

This application claims priority to U.S. Patent Application Ser. No. 62/406,287 titled "Console Positioning" and filed on 10 Oct. 2016, which application is herein incorporated by reference for all that it discloses.

BACKGROUND

Aerobic exercise is a popular form of exercise that improves one's cardiovascular health by reducing blood pressure and providing other benefits to the human body. Aerobic exercise generally involves low intensity physical exertion over a long duration of time. Typically, the human body can adequately supply enough oxygen to meet the body's demands at the intensity levels involved with aerobic exercise. Popular forms of aerobic exercise include running, jogging, swimming, and cycling, among others activities. In contrast, anaerobic exercise typically involves high intensity exercises over a short duration of time. Popular forms of anaerobic exercise include strength training and short distance running.

Many choose to perform aerobic exercises indoors, such as in a gym or their home. Often, a user will use an aerobic exercise machine to perform an aerobic workout indoors. One type of aerobic exercise machine is a treadmill, which is a machine that has a running deck attached to a support frame. The running deck can support the weight of a person using the machine. The running deck incorporates a conveyor belt that is driven by a motor. A user can run or walk in place on the conveyor belt by running or walking at the conveyor belt's speed. The speed and other operations of the treadmill are generally controlled through a control module that is also attached to the support frame and within a convenient reach of the user. The control module can include a display, buttons for increasing or decreasing a speed of the conveyor belt, controls for adjusting a tilt angle of the running deck, or other controls. Other popular exercise machines that allow a user to perform aerobic exercises indoors include elliptical trainers, rowing machines, stepper machines, and stationary bikes, to name a few.

One type of treadmill is disclosed in U.S. Patent Publication No. 2012/0220427 issued to Darren C. Ashby, et al. In this reference, an exercise system includes one or more exercise devices that communicate via a network with a communication system. The communication system stores and/or generates exercise programming for use on the exercise device. The exercise programming is able to control one or more operating parameters of the exercise device to simulate terrain found at a remote, real world location. The exercise programming can include images/videos of the remote, real world location. The control signals and the images/videos can be synchronized so that a user of the exercise device is able to experience, via the changing operating parameters, the topographical characteristics of the remote, real world location as well as see images of the location. Another type of treadmill is described in U.S. Patent Publication No. 2009/0209393 issued to Bradley A. Crater, et al. These references are incorporated by reference for all that they disclose.

SUMMARY

In one embodiment, a method for positioning a console of an exercise device includes determining an angle formed

2

between an exercise deck of the exercise device and a base of the exercise device, and adjusting a physical height of a console of the exercise device to a correlated height, relative to the base, based at least in part on the angle of the exercise deck.

The correlated height may have a proportional relationship with a change in the angle.

The correlated height may be based in part on a user preference.

10 The user preference may be stored in a user profile.

The correlated height may be based in part on a location of a load applied to the deck by the user during the performance of an exercise.

15 The method may include determining the location with at least one optical sensor.

The method may include determining the location with at least one load cell sensor.

20 Determining the angle may include determining a height of at least a portion of the deck with a distance sensor.

The sensor may be incorporated into the console.

25 The method may include determining the correlated height.

Determining the correlated height may include multiplying a change in the angle by a proportionality constant to determine a proportional height.

30 Determining the correlated height may further include adjusting the correlated height from the proportional height based on user preferences.

Determining the correlated height further may include adjusting the correlated height from the proportional height based on a location of a load applied to the deck by the user during the performance of an exercise.

35 Determining the angle may automatically occur in response to activating an incline mechanism.

In one embodiment, a method for positioning a console of an exercise device includes determining an angle formed between an exercise deck of the exercise device and a base of the exercise device and adjusting a physical height of a console of the exercise device to a correlated height based at least in part on the angle of the exercise deck and a user preference.

40 Determining the correlated height may include multiplying a change in the angle by a proportionality constant to determine a proportional height.

Determining the correlated height may include adjusting the correlated height from the proportional height based on user preferences.

45 Determining the correlated height may include adjusting the correlated height from the proportional height based on a location of a load applied to the deck by the user during the performance of an exercise.

50 Determining the angle may occur automatically in response to activating an incline mechanism.

In one embodiment, a method for positioning a console of an exercise device includes determining an angle formed between an exercise deck of the exercise device and a base of the exercise device by multiplying a change in the angle by a proportionality constant to determine a proportional height, refining the correlated height from the proportional height based on user preferences and a location of a load applied to the deck by the user during the performance of an exercise, where the determining the angle occurs automatically in response to activating an incline mechanism, and adjusting a physical height of a console of the exercise

device to a correlated height based at least in part on the angle of the exercise deck and a user preference.

BRIEF DESCRIPTION OF THE DRAWINGS

The accompanying drawings illustrate various embodiments of the present apparatus and are a part of the specification. The illustrated embodiments are merely examples of the present apparatus and do not limit the scope thereof.

FIG. 1 illustrates a perspective view of an example of a treadmill in a neutral position in accordance with the present disclosure.

FIG. 2 illustrates a perspective view of an example of a treadmill in an inclined position in accordance with the present disclosure.

FIG. 3 illustrates a perspective view of an example of a sensor incorporated into a console in accordance with the present disclosure.

FIG. 4 illustrates a side view of an example of a treadmill in accordance with the present disclosure.

FIG. 5 illustrates a perspective view of an example of an adjusting system in accordance with the present disclosure.

FIG. 6 illustrates a side view of an example of a treadmill in accordance with the present disclosure.

FIG. 7 illustrates a side view of an example of a treadmill in accordance with the present disclosure.

FIG. 8 illustrates a side view of an example of a treadmill in accordance with the present disclosure.

FIG. 9 illustrates a side view of an example of a treadmill in accordance with the present disclosure.

FIG. 10 illustrates a method of an example of positioning a console in accordance with the present disclosure.

FIG. 11 illustrates a method of an example of positioning a console in accordance with the present disclosure.

Throughout the drawings, identical reference numbers designate similar, but not necessarily identical, elements.

DETAILED DESCRIPTION

For purposes of this disclosure, the term “aligned” means parallel, substantially parallel, or forming an angle of less than 35.0 degrees. For purposes of this disclosure, the term “transverse” means perpendicular, substantially perpendicular, or forming an angle between 55.0 and 125.0 degrees. Also, for purposes of this disclosure, the term “length” means the longest dimension of an object. Also, for purposes of this disclosure, the term “width” means the dimension of an object from side to side. For the purposes of this disclosure, the term “above” generally means superjacent, substantially superjacent, or higher than another object although not directly overlying the object. Further, for purposes of this disclosure, the term “mechanical communication” generally refers to components being in direct physical contact with each other or being in indirect physical contact with each other where movement of one component affects the position of the other.

FIG. 1 depicts an example of a treadmill 100 having a deck 102 with a first pulley disposed in a front portion of the deck 102 and a second pulley incorporated into a rear portion of the deck 102. A tread belt 104 surrounds the first pulley and the second pulley. A motor is in mechanical communication with either the first pulley or the second pulley.

The rear portion of the deck 102 is attached to a base member 106 of the treadmill’s frame. A pivot connection 110 between the rear portion of the deck 102 and the base member 106 allows the front portion of the deck 102 to

incline upwards or decline downwards. When the deck 102 inclines or declines, the base member 106 remains stationary.

A first side post 112 is attached to a first side of the base member 106, and a second side post 114 is attached to a second side of the base member 106. In the example depicted in FIG. 1, the first side post 112 and the second side post 114 also remain stationary as the deck 102 inclines and/or declines. The first side post 112 and the second side post 114 collectively support a console 116. The console 116 includes a display 118 and an input mechanism 120 for controlling the deck’s incline angle.

A sensor 122 is incorporated into the console 116. In some examples, the sensor 122 is a distance sensor that is oriented to determine the distance between the deck 102 and the console 116. As the deck 102 moves relative to the console 116, the sensor 122 can determine the movement changes. In response to the movement changes, the sensor 122 can send a message to actuators to cause the console to move so that the console 116 and the deck 102 can maintain a predetermined distance from one another.

FIG. 2 depicts an example of a treadmill 200. In this example, the deck 202 is inclined so that the front portion of the deck 202 is elevated. The console 204 is also moved up and forward. In this example, the sensor 206 incorporated into the console 204 detects that the deck’s distance from the console 204 changed. As a result, the sensor sends a signal to a processor to generate control signals to cause the console 204 to move a distance proportional to the distance that the deck 202 moved relative to the console 204.

FIG. 3 depicts an example of a sensor 300 incorporated into a console 302 of a treadmill. In this example, the sensor 300 is secured to the underside 304 of the console 302. In some cases, the sensor 300 is a camera with an ability to send an optical or other signal towards the deck and measure the time that the reflection of the signal takes to return to the sensor 300. This time-of-flight measurement may be recorded by the sensor 300 and sent to a processor that sends directions to actuators to orient the console. In some cases, the processor causes the height of the console to change. In different examples, the processor causes the angle of the console to change. In yet other situations, the processor causes the forward position of the console to change. In an additional example, the processor causes the angle, forward position, and the height of the console 302 to change in response to the time-of-flight measurement.

FIG. 4 depicts an example of a treadmill 400 from the side showing the deck 402 in a neutral position 401 in solid lines and showing the deck 402 in an inclined position 404 in dashed lines. The console 406 is moved forward and up when the deck 402 is in the inclined position versus when the deck 402 is in the neutral position.

In this example, at least one of the side posts 408 includes a series of magnetic sensors 410 that are located to sense the incline position of the deck 402. The side of the deck 402 may incorporate a least one magnet (not shown) so that when the deck is moved into a position that is adjacent to one of the magnetic sensors 410, the magnetic sensor 410 can have a signal strength that indicates that the deck 402 is positioned at an angle that is known to the processor. In response, the processor can send a signal to the actuators to change the console’s position and orientation based on the deck’s orientation.

FIG. 5 depicts an example of an adjusting system 500. In this example, the adjusting system 500 includes processing resources 502 and memory resources 504. The memory resources 504 may cause the processing resources 502 to

carry out functions programmed in the memory resources 504. In this example, the memory resources 504 include a distance determiner 506, a user profile database 512 that includes a user height 514 and a user preference 516, a rotary actuator controller 508, and a linear actuator controller 510.

The processing resources 502 may be in communication with I/O resources, which may include a receiver, a transmitter, a transceiver, another type of communication device, or combinations thereof. Further, the processing resources 502 may be in direct communication or in communication through the I/O resources with a sensor 518, an incline mechanism 520, a rotary console actuator 522, and a linear console actuator 524.

FIG. 6 depicts an example of a treadmill 600 with an upright portion 602 and a base 604. A console 606 is movably attached to the upright portion 602, and an exercise deck 608 is pivotally attached to the base 604 at a rear end 610. The console 606 is located at a correlated height based on the angle that is formed between the exercise deck 608 and the base 604.

FIG. 7 depicts an example of a treadmill 700 with a greater angle 701 formed between the base 702 and the exercise deck 704. In this example, the console 706 is also located at a correlated height which is based at least in part on the angle of the exercise deck 704. In some cases, the correlated height is also based at least in part on at least one user preference.

FIG. 8 depicts an example of a treadmill 800 where the angle between the exercise deck 802 and the base 804 is substantially zero. In this example, a load "L" is applied to a central portion of the exercise deck 802. This location may be where the user applies a load to the treadmill when the user is walking and/or running on the exercise deck during the performance of a workout. A console 806 is positioned at a correlated height based at least in part on the substantially zero angle and the location where the user is applying the load.

FIG. 9 depicts an example of a treadmill 900 with an elevated exercise deck 902 that forms an angle 903 substantially greater than zero. In this example, the console 904 is positioned at a correlated height that is determined at least in part on the substantially greater than zero angle and the location where the user is applying the load.

FIG. 10 depicts an example of a method 1000 for positioning a console. In this example, the method 1000 includes determining 1002 an angle formed between an exercise deck of the exercise device and a base of the exercise device and adjusting 1004 a physical height of a console of the exercise device to a correlated height based at least in part on the angle of the exercise deck when the physical height is determined to be out of alignment with the correlated height.

FIG. 11 depicts an example of a method 1100 for positioning a console. In this example, the method 1100 includes determining 1102 an angle formed between an exercise deck of the exercise device and a base of the exercise device, multiplying 1104 the angle by a proportionality constant to determine a proportional height, adjusting 1106 the correlated height from the proportional height based on user preferences, adjusting 1108 the correlated height from the proportional height based on a location of a load applied to the deck by the user during the performance of an exercise, and adjusting 1110 a physical height of a console of the exercise device to a correlated height when the physical height is determined to be out of alignment with the correlated height.

General Description

In general, the invention disclosed herein may provide users with a treadmill that uses a method for moving a

console based on the angle formed between the exercise deck and a base of the treadmill. The method may include determining a proportional angle, based at least in part on the angle. The correlated angle may be changed from the proportional angle based on the user's preferences, a location that the user applies a force on the exercise deck during the performance of an exercise, other factors, or combinations thereof.

The exercise deck may include a platform that has a first 10 pulley located in a front portion of the deck and a second pulley located in a rear portion of the deck. A tread belt may surround the first and second pulleys and provide a surface on which the user may exercise. At least one of the first 15 pulley and the second pulley may be connected to a motor so that when the motor is active, the pulley rotates. As the pulley rotates, the tread belt moves as well. The user may exercise by walking, running, or cycling on the tread belt's moving surface. In other examples, the tread belt is moved with the user's own power. In these situations, the tread belt 20 may move as the user pushes off of the tread belt with his or her feet while walking or running. A flywheel may be connected to the tread belt and/or one of the pulleys to maintain the tread belt's momentum under the user's power.

The exercise deck may be capable of having its front 25 portion raised and lowered as well as its rear portion raised and lowered to control the lengthwise slope of the running deck. With these elevation controls, the orientation of the running deck can be adjusted as desired by the user or as instructed by a programmed workout. In those examples 30 where the treadmill is involved with simulating a route that involves changes in elevation, the running deck can be oriented to mimic the elevation changes in the route while the user performs an exercise on the deck.

In one example, the lengthwise slope and/or lateral tilt 35 angle of the exercise deck can be controlled with one or more actuators, often linear actuators, positioned at the corners of the deck. In another example, a single linear actuator positioned underneath the deck is attached to the deck's underside and a base of the deck. In this example, 40 when the single linear actuator extends, the single linear actuator increases the incline angle of the deck and when the single linear actuator retracts, the single linear actuator decreases the incline angle of the deck. In yet other examples, multiple actuators are used to adjust the incline angle simultaneously. Other types of actuators may be used, such as cam surfaces, magnets, hydraulic actuators, pneumatic actuators, other types of actuators, or combinations 45 thereof. Thus, in response to determining that the running deck's orientation should change, a signal can be sent to the actuators to appropriately move the deck into the desired orientation. The signal may come from the user's input, a simulated environment, a programmed workout, a remote device, another type of device or program, or combinations 50 thereof.

The treadmill includes a console attached to an upright 55 portion of the treadmill. In some cases, the upright portion includes a first post adjacent to a first side of the deck and a second post adjacent to a second side of the deck. In this example, the console is supported by the first and second deck. The deck moves independently of the first and second posts and also moves independently of the console.

The console may locate a display screen and the treadmill's controls within a convenient reach of the user to control the operating parameters of the exercise deck. For 60 example, the console may include controls to adjust the speed of the tread belt, adjust a volume of a speaker integrated into the treadmill, adjust an incline angle of the

running deck, adjust a decline of the running deck, adjust a lateral tilt of the running deck, select an exercise setting, control a timer, change a view on a display of the console, monitor the user's heart rate or other physiological parameters during the workout, perform other tasks, or combinations thereof. Buttons, levers, touch screens, voice commands, or other mechanisms may be incorporated into the console and can be used to control the capabilities mentioned above. Information relating to these functions may be presented to the user through the display. For example, a calorie count, a timer, a distance, a selected program, an incline angle, a decline angle, a lateral tilt angle, another type of information, or combinations thereof may be presented to the user through the display.

The treadmill may include preprogrammed workouts that simulate an outdoor route. In other examples, the treadmill has the capability of depicting a real world route. For example, the user may input instructions through the control console, a mobile device, another type of device, or combinations thereof to select a course from a map. This map may be a map of real world roads, mountain sides, hiking trails, beaches, golf courses, scenic destinations, other types of locations with real world routes, or combinations thereof. In response to the user's selection, the display of the control console may visually depict the beginning of the selected route. The user may observe details about the location, such as the route's terrain and scenery. In some examples, the display presents a video or a still frame taken of the selected area that represents how the route looked when the video was taken. In other examples, the video or still frame is modified in the display to account for changes to the route's location, such as real time weather, recent construction, and so forth. Further, the display may also add simulated features to the display, such as simulated vehicular traffic, simulated flora, simulated fauna, simulated spectators, simulated competitors, or other types of simulated features. While the various types of routes have been described as being presented through the display of the control console, the route may be presented through another type of display, such as a home entertainment system, a nearby television, a mobile device, another type of display, or combinations thereof.

In addition to simulating the route through a visual presentation of a display, the treadmill may also modify the orientation of the running deck to match the inclines and slopes of the route. For example, if the beginning of the simulated route is on an uphill slope, the running deck may be caused to alter its orientation to raise the front portion of the running deck. Likewise, if the beginning of the simulated route is on a downward slope, the rear portion of the running deck may be caused to elevate to simulate the decline in the route. Also, if the route has a lateral tilt angle, the running deck may be tilted laterally to the appropriate side of the running deck to mimic the lateral tilt angle.

While the programmed workout or the simulated environment may send control signals to orient the deck, the user may, in some instances, override these programmed control signals by manually inputting controls through the console. For example, if the programmed workout or the simulated environment cause the deck to be steeper than the user desires, the user can adjust the deck's orientation with the controls in the console.

Any appropriate type of actuator may be used in accordance with the principles described herein. For example, a non-exhaustive list of linear actuators that may be used includes screw actuators, hydraulic actuators, pneumatic actuators, solenoids, magnetic actuators, cams, electro-mechanical actuators, telescoping actuators, other types of

linear actuators, other types of actuators, or combinations thereof. Further, the actuators may be powered with a motor, compressed gas, electricity, magnetic fields, other types power sources, or combinations thereof. Further, the actuators may also have the ability to laterally tilt the running deck to any appropriate angle formed between a running surface of the running deck and the surface upon which the treadmill rests. For example, the range of the lateral tilt angle may span from negative 55 degrees to positive 55 degrees, or any range there between.

In some examples, the treadmill includes a sensor that measures the distance that the deck is away from the console. This sensor may be in communication with a processor of the console adjusting system. This processor may also control actuators that move the console in response to determining that the distance between the console and the deck has changed. For example, in those situations where the sensor measures that the deck has been moved such that it is closer to the console than originally positioned, the actuators move the console farther away from the deck to maintain a predetermined distance between the deck and the console. Similarly, in those situations where the sensor measures that the deck is farther away from the console, the actuators move the console closer from the deck to maintain a predetermined distance between the deck and the console.

The console may be moved by any appropriate mechanism. In some examples, the console is moved with a vertical actuator. The vertical actuator may be positioned to move the console in a vertical direction. The vertical actuator may be a linear actuator or another type of actuator. Further, the vertical actuator may include a magnetic mechanism, a rack and pinion, a solenoid, a pneumatic mechanism, a hydraulic mechanism, another type of mechanism, or combinations thereof to cause the console to move. Likewise, the console may be moved with a horizontal actuator that is positioned to move the console in a horizontal direction. This horizontal actuator may be a linear actuator or another type of actuator as listed above.

Further, the console may be tilted into any appropriate orientation based on the position of the deck. In this example, the console may be pivotally connected to the upright portion. In some cases, as the incline angle of the deck increases, the console pivots forward so that the console maintains the same angular orientation relative to the user. Further, in some examples, when the incline angle decreases, the console pivots downward so that the console maintains the same angular orientation relative to the user.

In one example, the console is attached to a tray that is connected to the upright structure of the treadmill. In this example, the console can move along a track formed in the tray. In some examples, the tray can also pivot. In this example, the console can move with respect to the tray in a vertical direction and the tray can be rotated in response to the changes in the deck's incline angle.

In another example, the console may be connected to the upright portion through a track in the posts or another portion of the upright structure. In this example, the console is moved along the track in response to changes in the deck's incline angle. The movement along the track may be powered by a motor, a rack and pinion, a linear actuator, another type of actuator, or combinations thereof. The track may be a substantially straight track. In other examples, the track has at least a curved portion.

A distance sensor may be incorporated into the console which detects the distance that the deck is away from the console. In this example, the distance sensor may be a time-of-flight sensor that sends a signal towards the deck

and measures the time for the signal's reflection to return to the sensor. The time-of-flight sensor may be an acoustic sensor, an infrared sensor, a radio frequency sensor, an ultrasonic sensor, a laser sensor, another type of sensor, or combinations thereof.

The distance sensor may be incorporated into any appropriate location of the treadmill. For example, the distance sensor may be incorporated into the underside of the console, the top side of the deck, an upright structure, a frame of the treadmill, another component of the treadmill, or combinations thereof. In some cases, the sensor is an integral feature of the treadmill. In yet other cases, the sensor is attachable to the outside of the treadmill.

The distance sensor may be continuously monitoring the distance between the console and the deck. In other examples, the distance sensor takes a measurement of the distance between the deck and the console at predetermined intervals. In yet other examples, the sensor takes a measurement when triggered by an appropriate event. An incline mechanism may send a signal to the processor when the incline mechanism is about to move, is currently moving, or has finished changing the incline angle of the deck. In response to receiving the signal from the incline mechanism, the processor can send instructions to the distance sensor to take a distance measurement. In response to determining the change in the distance, the processor can instruct the actuators that cause the console to move to make an adjustment.

In another example, the sensor is incorporated into the posts of the upright structure. As the front portion of the deck moves with respect to the posts based on the deck's incline angle, the sensor in the posts can determine the location of the deck and send the location information to the processor. For example, a series of magnetic sensors may be positioned along a portion of the posts' length. One of the magnetic sensors may be located in the neutral position so that the magnetic sensor senses that the deck is adjacent to the neutral magnetic sensor when the deck is in the neutral position. An object with a recognizable magnetic field may be incorporated into the deck so that the magnetic sensors can detect the presence of the deck when the deck is adjacent to the magnetic sensors. In one example, the object incorporated into the deck may be a magnet with a strong enough magnetic field strength that the magnetic sensor can detect the object's presence and therefore detect the presence of the deck. In another example, the object has an identifiable magnetic signature that allows the magnetic sensor to distinguish the presence of the object incorporated in the deck from other items that have a magnetic field.

In one situation, the deck may be inclined so that the front portion of the deck moves to be adjacent to a magnetic sensor located above the neutral sensor. In at least one instance, the deck may be moved so that the front portion of the deck is located adjacent to a third or fourth magnetic sensor that is located above the neutral magnet. In another example, the deck may be declined so that the magnetic sensors located below the neutral magnetic sensor detect that the front portion of the deck is located proximate to them. Depending on the location of the deck, one or more of the magnetic sensors may indicate that the deck is located proximate to the deck. While this example has been described with magnetic sensors incorporated into the upright structure to determine whether the front portion of the deck is adjacent, any appropriate type of sensor may be used. For example, the sensors incorporated into the upright structure may include optical sensors, time-of-flight sensors, push sensors, level sensors, other types of sensors, or combinations thereof.

In another example, the sensor is an optical sensor that may be incorporated into the console, incorporated into the upright structure of the console, incorporated into the deck, incorporated into another portion of the treadmill, or combinations thereof. The optical sensor may be positioned so that the deck is in the optical sensor's field of view. The optical sensor may include a position that the optical sensor understands to be a neutral baseline and when the deck is aligned with the neutral baseline, the optical sensor determines that the deck is in a neutral position. When the deck is angularly offset from the neutral baseline, the optical sensor can measure the angular offset to determine the deck's incline angle.

The console may move at the same time that the deck moves. In this example, the console is continuously adjusted in real time for the changes in the deck's incline angle. In other examples, the console moves after a delay after changing the deck's incline angle. In some situations, the console can be moved to one of multiple preset locations and/or preset angular orientations. In yet other situations, the console can be moved to any position or angular orientation within the ranges that the console can move.

The adjusting system for changing the position and/or orientation of the console may include a combination of hardware and programmed instructions for executing the functions of the adjusting system. The adjusting system may include processing resources that are in communication with memory resources. Processing resources include at least one processor and other resources used to process the programmed instructions. As described herein, the memory resources may represent generally any memory capable of storing data such as programmed instructions or data structures used by the adjusting system.

The processing resources may include I/O resources that are capable of being in communication with a remote device that stores the user information, user preferences, programmed workouts, simulated workouts, other types of information, or combinations thereof. The remote device may be a mobile device, a cloud based device, a computing device, another type of device, or combinations thereof. In some examples, the adjusting system communicates with the remote device through a mobile device which relays communications between the adjusting system and the remote device.

The remote device may execute a program that can provide useful information to the adjusting system. An example of a program that may be compatible with the principles described herein includes the iFit program which is available through www.ifit.com identified above. An example of a program that may be compatible with the principles described in this disclosure is described in U.S. Pat. No. 7,980,996 issued to Paul Hickman. U.S. Pat. No. 7,980,996 is herein incorporated by reference for all that it discloses. In some examples, the user information accessible through the remote device includes the user's age, gender, body composition, height, weight, health conditions, other types of information, or combinations thereof.

The processing resources, memory resources, and remote devices may communicate over any appropriate network and/or protocol through the input/output resources. In some examples, the input/output resources include a transmitter, a receiver, a transceiver, or another communication device for wired and/or wireless communications. For example, these devices may be capable of communicating using the ZigBee protocol, Z-Wave protocol, BlueTooth protocol, Wi-Fi protocol, Global System for Mobile Communications (GSM) standard, another standard, or combinations thereof. In other

11

examples, the user can directly input some information into the actuation system through a digital input/output mechanism, a mechanical input/output mechanism, another type of mechanism, or combinations thereof.

The memory resources may include a computer readable storage medium that contains computer readable program code to cause tasks to be executed by the processing resources. The computer readable storage medium may be a tangible and/or non-transitory storage medium. The computer readable storage medium may be any appropriate storage medium that is not a transmission storage medium. A non-exhaustive list of computer readable storage medium types includes non-volatile memory, volatile memory, random access memory, write only memory, flash memory, electrically erasable program read only memory, magnetic based memory, other types of memory, or combinations thereof.

The memory resources may include a distance determiner that represents programmed instructions that, when executed, cause the processing resources to determine the distance that the console is from the deck. The distance determiner may determine the distance based on a measurement from the sensor. In another example, the adjusting system uses another mechanism for determining the distance of the deck from the console.

The memory resources may also include a profile user database that includes information about the user that affects the position and/or orientation of the console. In some examples, the profile user database includes a user height, a user preference, another characteristic about the user, or combinations thereof.

In some examples, the memory resources include a rotary actuator controller that represents programmed instructions that, when executed, cause a rotary console actuator to rotate the orientation of the console so that the console maintains a relative angle with the user despite a change in the deck's incline angle. Further, the memory resources may include a linear actuator controller that represents programmed instructions that, when executed, cause a linear console actuator to move the console in a linear direction based on the incline angle of the deck. In some cases, the linear direction includes a vertical direction, a horizontal direction, a diagonal direction, another type of direction, or combinations thereof.

Further, the memory resources may be part of an installation package. In response to installing the installation package, the programmed instructions of the memory resources may be downloaded from the installation package's source, such as a portable medium, a server, a remote network location, another location, or combinations thereof. Portable memory media that are compatible with the principles described herein include DVDs, CDs, flash memory, portable disks, magnetic disks, optical disks, other forms of portable memory, or combinations thereof. In other examples, the program instructions are already installed. Here, the memory resources can include integrated memory such as a hard drive, a solid state hard drive, or the like.

In some examples, the processing resources and the memory resources are located within the treadmill, a mobile device, an external device, another type of device, or combinations thereof. The memory resources may be part of any of these device's main memory, caches, registers, non-volatile memory, or elsewhere in their memory hierarchy. Alternatively, the memory resources may be in communication with the processing resources over a network. Further, data structures, such as libraries or databases containing user and/or workout information, may be accessed from a remote

12

location over a network connection while the programmed instructions are located locally.

While the examples above have been described with reference to changing the position and/or orientation of the console based on the incline angle of the deck, any appropriate parameter of the deck may be used to trigger a change in the console's position and/or orientation. For example, changing the position and/or orientation of the console may be triggered by changing the side to side tilt of the deck, the overall height of the deck, another parameter of the deck, or combinations thereof.

In some cases, the incline mechanism sends instructions to the console to move the position and/or orientation of the console based on the changes in the deck's incline angle. In this situation, the sensor may confirm the distance between the deck and the console. In this type of example, the actuators that move the console may be triggered to move the console in response to receiving the confirmation.

The position of the console may change based on the angle of the deck, user preferences, the load applied to the deck, other factors, or combinations thereof. The correlated height of the console may be the desired height of the console for the user, which changes as the angle of the exercise deck changes. For example, when the angle between the exercise deck and the base is substantially zero, the correlated height of the console may be at an initial height (H_i). The H_i may be measured relative to a support surface on which the treadmill is situated or measured relative to a front portion of the base, a front portion of the deck, another portion of the treadmill, or combinations thereof. When the angle changes, a proportionality constant (C_p) may be multiplied by the angle change ($\Delta\alpha$). The product of the C_p and $\Delta\alpha$ can be used to modify H_i to arrive at the correlated height (H_c). Thus, in this example, the correlated height may be represented by

$$H_c = H_i + (C_p \times \Delta\alpha).$$

For example, if the initial height is 4.0 feet and the proportionality constant is 0.1, when the angle changes 1.0 degree, the correlated height becomes 4.1 feet. In this example, the correlated height equals a proportional height (H_p). In other words, $H_c = H_p$ in some instances. The proportionality constant (C_p) may be determined from a trigonometric relationship of the angle change ($\Delta\alpha$) and the relative change in height as determined by the length of the base times the tangent of the deck angle relative to the base.

In other examples, the correlated height may be affected by additional factors other than just the proportionality height. For example, the user's preferences (P_u) and where the user applies a load (L_u) onto the exercise deck during the performance of an exercise may be factors that make up the correlated height. In an example where the correlated height is affected by user preferences, the correlated height may be represented by

$$H_c = H_p + P_u$$

In this example, if the user's preference is -0.2, and the proportional height is 4.1 feet as in the above example, then the correlated height is 3.9 feet.

In an example where the location of the user's load affects the correlated height, the correlated height may be represented as follows:

$$H_c = (H_p) - (L_u \times L_c)$$

In this representation, L_c represents a location constant. In one example, the user's location may be 1.5 feet away from the console on the exercise deck. The location constant may

be 0.05. Thus, in this example, product of the user's location and the location constant equals 0.075. Accordingly, the 0.075 is subtracted from the proportional height. In those examples where the proportional height is 4.1 feet, the correlated height in this case is 4.025 feet.

In some cases, both the user preferences and the user's location can be used to determine the correlated height. In one particular example, the correlated height may be represented as

$$H_c = (H_p + P_u) - (L_u \times L_c)$$

Thus, in this example, the correlated height is determined by finding the proportional height and adjusting the proportional height with the user's preference. Then, the combination of the user's preference and the proportional height can be modified by the user's location. Keeping with the examples above where the proportional height is 4.1 feet, the user's preference is -0.2 feet, the user's location is 1.5, and the location constant is 0.05, then this representation of the correlated constant above equals 3.825 feet.

In yet another example, the user's location may be determined before the user's preference is applied. In one of these cases, the correlated height may be represented as

$$H_c = (H_p - (L_u \times L_c)) + P_u$$

In keeping with the above examples where the proportional height is 4.1 feet, the user's preference is -0.2 feet, the user's location is 1.5, and the location constant is 0.05, then this representation of the correlated constant above also equals 3.825 feet.

While the examples above have been described with reference to a particular proportionality constant, any appropriate value for the proportionality constant may be used in accordance with the principles described herein. For example, the proportionality constant may include a value that is greater than -1.0 and less than 1.0.

While the examples above have been described with reference to a particular location constant, any appropriate value for the location constant may be used in accordance with the principles described herein. For example, the location constant may include a value that is greater than -1.0 and less than 1.0.

While the examples above have been described with reference to a particular initial height, any appropriate value for the initial height may be used in accordance with the principles described herein. For example, the initial height may include a value that is greater than 1.0 feet and less than 7.0 feet.

While the examples above have been described with reference to a particular user preference, any appropriate value for the user preference may be used in accordance with the principles described herein. For example, the user preference may include a value that is greater than -5.0 feet and less than 5.0 feet.

While the examples above have been described with reference to a particular user location, any appropriate value for the user location may be used in accordance with the principles described herein. For example, the user location may include a value that is greater than zero inches and less than a distance that equals a length of the exercise deck.

While the examples above have been described with reference to a particular angle formed between the base and the exercise deck, any appropriate value for the angle may be used in accordance with the principles described herein. For example, the angle may include a value that is greater than -25.0 degrees and less than 45.0 degrees.

Any appropriate trigger may initiate the process of adjusting the console to the correlated height. In some examples, the process is triggered when the incline mechanisms changes the angle of the exercise deck. In other examples, the process is triggered when the user sends a command to the treadmill to initiate the process. These types of commands may be sent to the treadmill through an input mechanism incorporated into the console, an input mechanism incorporated into a networked device, an input mechanism incorporated into a remote device, an input mechanism incorporated into another location on the treadmill, a speech command, a microphone, a button, a touchscreen, another type of input mechanism, or combinations thereof.

15 What is claimed is:

1. A method for positioning a console of an exercise device comprising a base, an exercise deck, at least one telescopic post and the console, wherein the exercise deck is adjustably attached to the base and the console is attached to the base through the at least one telescopic post, the method comprising:

determining an angle of the exercise deck of the exercise device, wherein the angle of the exercise deck is formed between the exercise deck and the base of the exercise device, and wherein the angle of the exercise deck is determined with a sensor incorporated into the console, the console and the exercise deck being supported by the base of the exercise device; and
30 adjusting a physical height of the console of the exercise device to a correlated height based at least in part on the angle of the exercise deck.

2. The method of claim 1, further including determining the correlated height.

3. The method of claim 2, wherein determining the correlated height includes multiplying a change in the angle of the exercise deck by a proportionality constant to determine a proportional height.

4. The method of claim 3, wherein determining the correlated height further includes adjusting the correlated height based on the proportional height, the proportional height being based on user preferences.

5. The method of claim 3, wherein determining the correlated height further includes adjusting the correlated height based on the proportional height, the proportional height being based on a location of a load applied to the exercise deck by a user during a performance of an exercise.

6. The method of claim 1, wherein the correlated height is based in part on a location of a load applied to the exercise deck by a user during a performance of an exercise.

7. The method of claim 6, further including determining the location of the load applied by the user with at least one optical sensor.

8. The method of claim 6, further including determining the location of the load applied by the user with at least one load cell sensor.

9. The method of claim 1, wherein the correlated height is based in part on a user preference.

10. The method of claim 9, wherein the user preference is stored in a user profile.

11. The method of claim 1, wherein determining the angle of the exercise deck includes determining a height of at least portion of the exercise deck with a distance sensor.

12. The method of claim 11, wherein the distance sensor is incorporated into the console.

13. The method of claim 1, wherein the correlated height has a proportional relationship with a change in the angle of the exercise deck.

15

14. The method of claim 1, wherein the determining the angle of the exercise deck occurs automatically in response to a change in an incline angle of the exercise deck.

15. A method for positioning a console of an exercise device comprising a base, an exercise deck, at least one telescopic post and the console, wherein the exercise deck is adjustably attached to the base and the console is attached to the base through the at least one telescopic post, the method comprising:

measuring a distance between the console and the exercise deck using a sensor incorporated into the console,

the console and the exercise deck being supported by the base of the exercise device;

determining an angle of the exercise deck of the exercise device, wherein the angle of the exercise deck is formed between the exercise deck and the base of the exercise device, wherein the angle of the exercise deck is determined based on the distance between the console and the exercise deck; and

adjusting a physical height of the console of the exercise device to a correlated height based at least in part on the angle of the exercise deck and a user preference.

16. The method of claim **15**, wherein determining the correlated height includes multiplying a change in the angle of the exercise deck by a proportionality constant to determine a proportional height.

17. The method of claim 16, wherein determining the correlated height further includes adjusting the correlated height based on the proportional height, the proportional height being based on user preferences.

18. The method of claim 16, wherein determining the

correlated height further includes adjusting the correlated height based on the proportional height based, the propor-

16

tional height being based on a location of a load applied to the exercise deck by a user during a performance of an exercise.

19. The method of claim 15, wherein the determining the angle of the exercise deck occurs automatically in response to a change in an incline angle of the exercise deck.

20. A method for positioning a console of an exercise device comprising a base, an exercise deck, at least one telescopic post and the console, wherein the exercise deck is adjustably attached to the base and the console is attached to the base through the at least one telescopic post, the method comprising:

determining an angle of the exercise deck of the exercise device, wherein the angle of the exercise deck is formed between the exercise deck and the base of the exercise device in response to a change in an incline angle of the exercise deck, wherein the angle of the exercise deck is determined using a sensor incorporated into the console, the console and the exercise deck being supported by the base of the exercise device the exercise device;

multiplying a change in the angle of the exercise deck by a proportionality constant to determine a proportional height:

determining a correlated height from the proportional height based on at least one user preference and a location of a load applied to the exercise deck by a user during a performance of an exercise; and

adjusting a physical height of the console of the exercise device to the correlated height based at least in part on the angle of the exercise deck and a user preference when the physical height is determined to be out of alignment with the correlated height.
